SHUTTLE TENSION AND TAKE-UP DEVICE

Philip L. Spencer, Millbury, Mass., assignor to
Watson-Williams Manufacturing Company,
Millbury, Mass., a corporation of Massachusetts

Application December 22, 1932, Serial No. 648,457

6 Claims. (Cl. 139—215)

This invention relates to self-threading shuttles such as are used in automatic weft replenishing looms. It is desirable, particularly when using very fine weft such as silk or rayon, that provision be made in the shuttle for taking up slack in the weft during the weaving operation, as well as for applying tension thereto.

It is the general object of my present invention to provide an improved tension and take-up device for a self-threading shuttle, so designed that it may be easily and economically manufactured and that it will be exceptionally reliable when in use.

A further object is to provide a tension and take-up device which does not require increased shuttle space for its installation, and which is preferably mounted in a rear portion of the threading block itself.

My invention further relates to arrangements and combinations of parts which will be herein-after described and more particularly pointed out in the appended claims.

A preferred form of the invention is shown in the drawings, in which

Fig. 1 is a plan view of a portion of a shuttle embodying my improvements;

Fig. 2 is a side elevation thereof;

Fig. 3 is an enlarged sectional side elevation, taken along the line 3—3 in Fig. 1;

Fig. 4 is a transverse sectional elevation, taken along the line 4—4 in Fig. 3;

Fig. 5 is an end view of my improved tension and take-up member;

Fig. 6 is a side elevation thereof;

Fig. 7 is an enlarged sectional plan view, taken along the line 7—7 in Fig. 3;

Fig. 8 is a sectional side elevation similar to Fig. 3 but showing the parts in different positions;

Fig. 9 is a partial plan view showing a slight modification, and

Fig. 10 is an end view looking in the direction of the arrow 10 in Fig. 9.

Referring to the drawings, I have shown portions of a shuttle S and bobbin B, the bobbin having weft W wound thereon. The front portion of the shuttle is provided with a recess 10 (Fig. 7) to receive the threading block 11, and with a side opening 12 communicating with the recess 10 and forming a passage for the out-going weft.

The threading block 11 in its threading features is of a usual commercial construction and in that respect forms no part of my present invention. As shown in the drawings, the block 11 comprises a horn 13 projecting inwardly and downwardly

below an overlapping guide flange 14. The parts 13 and 14 are spaced apart to provide a passage 15 (Fig. 2) through which the weft W is threaded.

The usual steel or porcelain guide-pins 17, 18 and 19 (Fig. 7) are provided along the outlet passage 12 to take the wear of the rapidly moving weft W as it is drawn out of the shuttle.

The block 11 is also provided with a vertical slot or opening 20 (Figs. 1 and 7) through which the weft enters, and also with a longitudinally extended recess 22 and rear flange or partition 23. The portion 23 is provided with a thread passage 24 (Figs. 3 and 7) and with a narrow slot 25 (Fig. 1) through which the thread enters the passage 24.

My improved tension and take-up device comprises a pivoted member 30 (Figs. 5 and 6) preferably formed of sheet metal bent to substantially tubular shape and having separated side portions 31 and 32 (Fig. 5). The portions 31 and 32 are 20 spaced apart lengthwise of the member 30, as indicated in Fig. 6, to provide a threading space or opening 33. The lower edge of the member 31 is curved inward, as indicated at 35, to provide a hook-like portion effective to prevent unthreading.

A pivotal bearing portion 37 is formed on the outside of the tubular member 30, preferably by reversely bending a portion of the sheet metal as clearly indicated in Fig. 6. The bearing portion 37 is slotted at an intermediate point, as indicated at 38 in Fig. 5, for a purpose to be described.

The tension and take-up member 30 is mounted in the shuttle opening or recess 22 by inserting a pin 40 through the side walls of the recess and through the bearing portion 37, the member 30 being thus mounted for free pivotal movement in the recess 22.

A tension element 42, shown as a portion of a rubber band, has one end brought around to the back of the member 30 as clearly shown in Fig. 4, said end being then threaded downward through the slotted opening 38 and being knotted as indicated at 43.

The other end of the band 42 extends outward and rearward through a side opening 44 (Figs. 4 and 7) in the threading block 11 and thence into a side opening 45 (Fig. 7) in the body of the shuttle S, at which point the end of the band 42 is threaded through a transverse opening 46 in a tension screw 47.

The end of the band 42 is knotted at 48 to prevent withdrawal, and the yielding tension on the member 30 is adjusted by turning the screw 47,

this method of providing tension in shuttle mechanisms being quite common in the art.

Having described the construction and method of mounting my improved tension and take-up device, the operation thereof will be readily apparent by reference to Figs. 7 and 8. On the first pick of the shuttle, the weft W is guided into the openings 20 and 24 of the threading block and also through the opening 33 into the interior space of the tubular tension and take-up member 30.

During this threading operation, the member 30 is tipped forward from the upright position shown in Fig. 3 to the inclined position shown in dotted lines in Fig. 8. As the threading of the shuttle is thereafter completed, the weft moves to a lower position in the shuttle, as indicated in Fig. 8. When the weft is under tension in this normal lowered position, the weft moves the member 30 substantially to the horizontal position indicated in full lines in Fig. 8. The weft W in all positions bears against the flat rear side of the member 30, the upper edge of which may be rounded or beveled to prevent chaffing a fine weft thread.

The member 30 thus applies a light but continuous tension to the weft W and, as soon as any slackness of weft occurs, the tension and take-up member 30 swings upward to take up the slack, the member moving to the inclined position shown in dotted lines in Fig. 8 or even to the upright position indicated in Fig. 3.

In Figs. 9 and 10 I have shown a slightly modified construction in which the tension and take-up member 50 is pivoted in a casing or support 51 which is secured in an open-end groove or recess 52 in the rear portion of the threading block. Cross pins 53 may be used to secure the casing 51 in position in the recess 52. The rear wall of the casing 51 takes the place of the rear partition member 23 previously described and is provided with a slot 54 and thread opening 55 for guiding the thread to the tension and take-up member 50. The operation of this modified construction is exactly the same as in the form previously described, and the modified construction possesses certain advantages in manufacture.

I have thus provided a take-up and tension device conveniently mounted within the body of the threading block itself and so constructed that it will be automatically threaded on the first pick of the shuttle after insertion of the bobbin B therein. Furthermore, the device applies a continuous and uniform tension to the weft at all times and is effective to take up slack in the weft immediately upon the occurrence thereof.

It will be noted that the device is extremely simple and comprises a single movable part only, which part may be conveniently formed from a single piece of suitable sheet metal.

Having thus described my invention and the advantages thereof, I do not wish to be limited to the details herein disclosed, otherwise than as set forth in the claims, but what I claim is:

1. In a loom shuttle, a tension and take-up device comprising a member mounted on a transverse horizontal axis in said shuttle adjacent the shuttle-eye, and means to yieldingly move said

member toward upright position in the path of the weft, said member being displaceable therefrom by weft tension and being substantially tubular with side portions spaced apart to provide a longitudinal threading opening and with the inner edge of one side portion inwardly offset to provide a hook-like projection effective to prevent unthreading.

2. In a loom shuttle, a threading block having a longitudinally extended recess therein, and a tension and take-up device comprising a member pivotally mounted in said recess on a transverse horizontal axis, and means to yieldingly swing said member rearward and upward to substantially upright position in the path of the weft, said member comprising a single piece of sheet metal bent to provide a tubular thread-guiding portion and an extended and substantially continuous thread-engaging surface.

3. In a loom shuttle, a threading block having a longitudinally extended recess therein, a casing secured in said recess, a tension and take-up member mounted on a transverse horizontal axis in said casing, and means to yieldingly swing said member rearward and upward to substantially upright position in the path of the weft, said member being displaceable forwardly and downwardly to substantially horizontal position by weft tension thereon, and said casing having a rear end wall provided with an entrance slot 30 and a thread opening.

4. In a loom shuttle, a tension and take-up device comprising a member mounted on a transverse horizontal axis in said shuttle adjacent the shuttle-eye, and means to yieldingly move said member toward upright position in the path of the weft, said member being displaceable therefrom by weft tension thereon and providing a substantially tubular guide for the thread with a longitudinal threading opening in one wall portion thereof and with an extended and continuous thread-engaging surface.

5. In a loom shuttle, a tension and take-up device comprising a member mounted on a transverse horizontal axis in said shuttle adjacent the shuttle-eye, and means to yieldingly move said member toward upright position in the path of the weft, said member being yieldingly displaceable downwardly and forwardly from such position by weft tension thereon, said member constituting a substantially tubular guide for the thread with side portions of said tubular member spaced apart to provide a longitudinal threading opening.

6. In a loom shuttle, a threading block having a longitudinally extended recess therein, a tension and take-up device comprising a member mounted in said recess on a transverse horizontal axis, and means to yieldingly swing said member rearward and upward to substantially upright position in the path of the weft, said member presenting an extended continuous and substantially flat metal surface in the path of the weft and over which the weft is drawn, and said member being displaceable forwardly and downwardly to substantially horizontal position by weft tension thereon.

PHILIP L. SPENCER.
